UNITED STATES PATENT OFFICE.

JAMES J. MCARDLE, OF PAWTUCKET, RHODE ISLAND.

NUT-LOCK.

SPECIFICATION forming part of Letters Patent No. 615,877, dated December 13, 1898.

Application filed June 8, 1898. Serial No. 682,918. (No model.)

To all whom it may concern:

Be it known that I, JAMES J. MCARDLE, of Pawtucket, in the county of Providence and State of Rhode Island, have invented certain 5 new and useful Improvements in Nut-Locks; and I hereby declare that the following is a full, clear, and exact description of the same, reference being had to the accompanying drawings, forming part of this specification.

10 This invention has reference to an improvement in nut-locks for rail-joints; and it consists in the peculiar and novel construction of a bar which, forming the washers for two bolts, has the end formed to act on the two 15 nuts as a lock, as will be more fully set forth hereinafter.

Figure 1 is a perspective view of my improved nut-lock. Fig. 2 is a side view of a two-bolt rail-joint provided with my nut-lock. 20 Fig. 3 is a top view, and Fig. 4 a transverse sectional view, of the same.

In the drawings, *a a* indicate the rail ends; *b b*, the fish-plates. These may be of any of the usual forms used to unite the end of the 25 rails, bars, or plates together. *c c* are the heads of the screw-bolts *d d*, and *e e* the nuts.

The nut-lock is formed of a preferably rectangular bar *f*, the ends *f' f'* of which are of gradually-diminishing thickness and increasing 30 width, forming fishtail-shaped ends. The bar is bent, usually while hot, around a pin to form the eyes *f² f²*, and the ends are bent so as to bring the fishtail ends *f' f'* in the position to bear on the nuts. The central 35 portion of the bar *f* is bent to extend from one side of one of the eyes *f²* to the opposite side of the other eye, with or without the rectangular connecting-piece *f³*. The tail ends *f' f'* are bent so as to bring the plane of their 40 surfaces oblique to the plane of the rest of the bar *f* and to the fish-plates.

In using my improved nut-lock the eyes *f²* are passed over the bolts *d d*, so as to bear 45 on the fish-plate *b*. The nuts *e e* are now placed on the bolts, and, turning on the screw-

thread of the bolts, the corners of the nuts encounter the oblique surfaces of the tail ends *f' f'*, which, owing to the bends *f⁴ f⁴* and the resiliency of the metal, yield to the movement of the corners of the nuts, but bear on the sides 50 of the nuts and hold the same in the adjusted position. The portion of the bar *f* extending around the bolts forms substantial washers for the nuts *e e*. The resiliency of the metal is readily secured by quickly cooling the nut-lock after it has been bent while heated, and while the nuts are firmly held in the adjusted position against jars, accidental blows, or vibrations the nuts can be turned with a wrench 55 to tighten or loosen the same. The tail ends 60 will yield to the corners of the nuts in turning the same backward in loosening the nut, but not as readily as they will yield, owing to their oblique surfaces, in turning the nut forward to tighten the same. 65

Having thus described my invention, I claim as new and desire to secure by Letters Patent—

1. A nut-lock, consisting of the bar *f* bent to form the two eyes *f² f²*, the bends *f⁴ f⁴* and 70 the ends *f' f'*, the surfaces of the ends *f' f'* being oblique to the plane of the nut-lock, as described.

2. In a nut-lock, the combination with the fish-plate *b*, the bolts *d d* and the nuts *e e*, of 75 the bar *f* having the eyes *f² f²*, the ends *f⁴ f⁴* and the tail ends *f' f'* the plane of the wide surfaces of which are oblique to the plane of the fish-plate, said tail ends *f' f'* bearing on one side of the nut of one bolt and the opposite side of the nut of the other bolt; whereby the tightening up of the nuts is facilitated 80 and the nuts are held against jars in their adjusted positions, as described.

In witness whereof I have hereunto set my 85 hand.

JAMES J. MCARDLE.
